DESIGN FOR A FISHING FLOAT

Charles D. Myers, Oklahoma City, Okla.

Application April 30, 1938, Serial No. 76,900

Term of patent 14 years

To all whom it may concern:

Be it known that I, Charles D. Myers, a citizen of the United States, residing at Oklahoma City, in the county of Oklahoma and State of Oklahoma, have invented a new, original, and ornamental Design for a Fishing Float, of which the following is a specification, reference being had to the accompanying drawing, forming part thereof.

I claim:

The ornamental design for a fishing float, as shown.

CHARLES D. MYERS.
